CULTIVATOR TINE

Ary van der Lely, 10 Weverskade, Maasland, Netherlands, and Cornelis Johannes Gerardus Bom, 36 Esdoornlaan, Rozenburg, Netherlands

Filed Apr. 6, 1972, Ser. No. 241,893

Claims priority, application Switzerland Dec. 14, 1971

Term of patent 14 years

Int. Cl. D15—03

U.S. Cl. D40—1 E

FIG. 5

FIG. 1 is a side view of a cultivator tine showing our new design and mounted on a support; the broken lines are shown for illustrative purposes only.

FIG. 2 is a side elevation view in the direction of arrow II in FIG. 1.

FIG. 3 is a cross-section along the line III—III in FIG. 2.

FIG. 4 is a cross-section along the line IV—IV in FIG. 2.

FIG. 5 is a perspective view of the cultivator tine embodying our new design.

We claim:

The ornamental design for a cultivator tine, substantially as shown and described.
